PORTABLE FIREPLACE

Francis S. Faust, Buffalo, N. Y.

Application February 16, 1956, Serial No. 40,187

Term of patent 14 years

(Cl. D81—7)

Fig. 1.

Fig. 4.

Fig. 2.

Fig. 3.

Fig. 1 is a top plan view of the portable fireplace embodying my new design.

Fig. 2 is a front elevational view thereof.

Fig. 3 is a side elevational view thereof, the opposite side elevational view being substantially the same.

Fig. 4 is a bottom plan view thereof.

I claim:

The ornamental design for a portable fireplace, substantially as shown and described.
